(57) CLAIM

The ornamental design for oven mitt, as shown and described.

DESCRIPTION

FIG. 1 is a top perspective view of an oven mitt showing my new design;

FIG. 2 is a top plan view thereof;

FIG. 3 is a bottom plan view thereof;

FIG. 4 is rear elevation view thereof;

FIG. 5 is a front elevation view thereof;

FIG. 6 is a right side elevation view thereof; the left side being a mirror image; and,

FIG. 7 is a top and side perspective view thereof, showing the oven mitt in an exemplary use.

The broken lines showing a human hand and a cooking pot in FIG. 7 illustrate environmental subject matter and form no part of the claimed design. The remaining broken-line subject matter illustrates unclaimed features of the article to which the design is applied.
